(57) **CLAIM**

The ornamental design for a stand for a nail drill and controller as shown and described.

DESCRIPTION

FIG. 1 is a front view of a stand for a nail drill and controller having a non-transparent body;

FIG. 2 is a back view of the stand of FIG. 1;

FIG. 3 is a front view of the stand of FIG. 1, with a nail drill and controller shown in broken lines;

FIG. 4 is a left side view of the stand of FIG. 1;

FIG. 5 is a right side view of the stand of FIG. 1;

FIG. 6 is a top view of the stand of FIG. 1;

FIG. 7 is a bottom view of the stand of FIG. 2;

FIG. 8 is a front view of the stand for a nail drill and controller having a transparent body;

FIG. 9 is a back view of the stand of FIG. 8;

FIG. 10 is a front view of the stand of FIG. 8, with a nail drill and controller shown in broken lines;

FIG. 11 is a left side view of the stand of FIG. 8;

FIG. 12 is a right side view of the stand of FIG. 8;

FIG. 13 is a top view of the stand of FIG. 8;

FIG. 14 is a bottom view of the stand of FIG. 9;

The broken lines form no part of the claimed design.
